UNITED STATES PATENT OFFICE.

ANSEL N. HOVEY, OF JACKSON, MICHIGAN.

ADJUSTABLE SHELF-BRACKET.

SPECIFICATION forming part of Letters Patent No. 404,004, dated May 28, 1889.

Application filed February 16, 1889. Serial No. 300,143. (No model.)

To all whom it may concern:

Be it known that I, ANSEL N. HOVEY, of Jackson, in the county of Jackson and State of Michigan, have invented a new and useful 5 Improvement in Adjustable Shelf-Brackets, of which the following is a specification.

My invention relates to improvements in adjustable shelf-brackets; and the objects of my improvements are to secure cheapness of 10 construction, to do away with the necessity of using cores in casting the parts, and to secure a serviceable bracket which shall not be liable to accidental displacement. I attain these 15 objects by the apparatus illustrated in the accompanying drawings, in which—

Figure 1 is an isometric view of the supporting-arm and a portion of the standard. A part of the standard is broken away to show 20 the way in which the supporting-arm is secured thereto. Fig. 2 is a section of the standard, taken in the plane indicated by the lines $x x$, Fig. 1.

Similar letters refer to similar parts throughout both views.

25 A A is a standard. b is the base of said standard, and is extended forward to form a foot, c, which is perforated to allow the passage of a screw-shank to secure the lower end of the standard to the floor.

30 a a are side pieces, which are parallel to each other and are cast in one piece with the base b and cross-pieces d to form the standard A. The cross-pieces d are set back a short distance from the front of the standard A, so 35 that the side pieces, a a, shall form shoulders e e, to prevent the accidental lateral displacement of the lower portion of the shelf-supporting arm B.

The shelf-supporting arm B is provided with 40 a hook, f, adapted to pass between the cross-pieces d and rest upon and back of one of

said cross-pieces to secure the shelf-supporting arm B to the standard A.

g is a web forming a brace to the shelf-supporting arm B.

45 h is a foot upon the lower rear portion of the brace g. The foot h is formed at such a distance below the hook f that said foot shall rest against one of the cross-pieces d. The foot h is in width a little less than the distance between the inside faces of the side pieces, a a.

50 The weight of the shelf will hold the hook f in place and will hold the foot h against the cross-piece d and between the side pieces, a a.

55 The standard A and shelf-supporting arm B, as above described, may be cast without cores, and are usually ready to be put up as soon as taken from the sand; but if any roughness of the surfaces should occur all the 60 important surfaces are level and accessible to the grindstone and can be readily smoothed.

65 In the above-described apparatus the arm B is held firmly in place and is secure from accidental displacement.

Having fully described my invention, what I claim, and desire to secure by Letters Patent, is—

70 The combination of the standard A A, composed of the side pieces, a a, and cross-pieces d, said cross-pieces being set somewhat back from the front of said standard to form the shoulders e e, and the shelf-supporting arm B B, provided with the hook f, and a brace adapted to pass between the side pieces, a a, 75 and rest against the cross-pieces d, substantially as shown and described.

ANSEL N. HOVEY.
